UNITED STATES PATENT OFFICE.

MACKEY WELLS, OF MILWAUKEE, WISCONSIN, ASSIGNOR TO KERNER INCINERATOR CO., OF MILWAUKEE, WISCONSIN, A CORPORATION OF WISCONSIN.

DESIGN FOR A SMOKER'S ASH RECEPTACLE.

Application filed January 28, 1924. Serial No. 8,457. Term of patent 14 years.

To all whom it may concern:

Be it known that I, MACKEY WELLS, a citizen of the United States, residing at Milwaukee, in the county of Milwaukee and State of Wisconsin, have invented a new, original, and ornamental Design for Smokers' Ash Receptacles, of which the following is a specification, reference being had to the accompanying drawing, forming a part thereof.

The figure is a perspective view of a smoker's ash receptacle, showing my new design.

I claim:

The ornamental design for a smoker's ash receptacle, substantially as shown.

MACKY WELLS.
